CURRENT INTERRUPTING MEANS

Edmund O. Schweitzer, Jr., Northbrook, Ill.

Application February 20, 1936, Serial No. 64,800

5 Claims. (Cl. 200—146)

My invention relates generally to circuit opening and closing devices and it has particular relation to such devices of the non-arching type.

In the prior art considerable difficulty has been experienced in arcs drawn between the contact members of circuit opening devices. Because of such arcing there is a tendency for the contact members to be burned, thereby causing pitting of the contact surfaces and consequently poor contact conditions between the contact members. In many instances there is the danger that an inflammable gas may be ignited in the event that an arc occurs on the opening of contact members. Many devices have been proposed for extinguishing arcs when they are formed. However, insofar as I am aware, no one has ever proposed to prevent the formation of the arc on the opening of contact members by changing the conditions under which the contact members are opened or the final break in the circuit is effected.

In circuit opening devices of the metallic contact type, arcing is caused by the ionization of a portion of the surface of one or both of the contact members. The ionization is a function of the heat generated in the surface of the contact members by the current flowing therethrough at the time that they are separated. Since the specific heat of metal, particularly copper, is relatively low, there is a rapid vaporization of the metal in the contact surfaces of the contact members. The ionized particles form a conducting path between the contact members and it is this path which causes the arc to be sustained, the path being of relatively low resistance.

The object of my invention, generally stated, is to provide a circuit opening device which shall be simple and efficient in operation and which may be readily and economically manufactured and installed.

The principal object of my invention is to provide for breaking an electric circuit between two portions of a non-metallic conducting fluid.

Another important object of my invention is to provide for opening an electric circuit between quantities of non-metallic conducting liquid surrounding the contact members of a circuit breaking device.

Another object of my invention is to provide a conducting liquid container around each of the contact members of a circuit breaking device, together with means for relatively moving the contact members to open the circuit between the portions of the liquid in each container.

Another object of my invention is to provide

a circuit breaking device in which the main contact members are separated in a conducting liquid and the final break is effected between two portions of the conducting liquid.

Other objects of my invention will in part be obvious and in part appear hereinafter.

Accordingly, my invention is disclosed in the embodiment hereof shown in the accompanying drawing and comprises the features of construction, combination of elements and arrangement of parts which will be exemplified in the construction hereinafter set forth and the scope of the application of which will be indicated in the appended claims.

For more complete understanding of the nature and scope of my invention, reference may be had to the following detail description, taken in connection with the accompanying drawing, in which:

Figures 1, 2 and 3 are views, partly in side elevation and partly in section, showing different operating positions of my novel circuit breaking device.

According to my invention I provide for effecting the final break in a circuit opening device between two portions of conducting liquid, preferably of a non-metallic type, rather than between two metallic contact surfaces or between a conducting liquid and a metallic member. When this manner of opening an electric circuit is employed, I have found that there will be no ionized arc path set up by ionized particles as is the case when the circuit is broken between the metallic contact surfaces. The final break is effected entirely between two portions of a conducting liquid.

In order to form and sustain an arc there must be a certain amount of thermionic emission from one of the contact members between which the arc is formed. When the contact members are formed of a metal, such as copper, having a relatively low specific heat, there is a considerable amount of thermionic emission, as set forth hereinbefore, and therefore there is a tendency for an arc to form and to be sustained. For the same amount of heat energy involved, the rise in temperature of a non-metallic conducting liquid will be relatively small compared to the temperature rise of the metallic contact member. There is, therefore, no tendency for an arc to form or to be sustained. In addition, because of the cooling effect of the conducting liquid, a sufficiently high temperature necessary to produce the ionized arc path is not reached.

Referring now particularly to Figure 1 of the

drawing, the reference character 10 indicates a container having at the bottom thereof a fixed contact member 11 secured to the container by means of a bolt 12 forming a terminal connection thereto. A movable contact member 13 in the form of a rod of conducting material is provided, as illustrated, and is disposed to engage the fixed contact member 11. The contact member 13 may be moved into and out of engagement with the contact member 11 by any suitable means, not shown.

It will be observed that a liquid 15 is disposed within the container 10 and that its level is above the point where the contact members 11 and 13 are in mutual engagement. The conducting liquid 15 may be any of several non-metallic kinds; for example, dilute solutions of sulphuric acid, hydrochloric acid, zinc sulphate or copper sulphate, may be employed. In certain instances also a common salt solution may be used. It will be noted that the circuit is completed not only between the contact members 11 and 13, but also that it is completed through the conducting liquid 15. However, due to the fact that the resistance of the circuit including the contact members 11 and 13 is relatively small as compared to the resistance of the conducting liquid 15, comparative- ly little of the current flows through the liquid.

In order to provide for opening the circuit through two portions of the conducting liquid 15, an auxiliary container 16, preferably composed of insulating material, is provided and rotatably mounted at 17 on the movable contact member 13. It will be observed that the bottom of the auxiliary container 16 is recessed at 18 and that a tipping member 19 is provided, the upper portion 20 of which is arranged to engage the recessed portion 18. The tipping member 19 is illustrated as being a continuation of the fixed contact member 11. However, it will be understood that it may be mounted as a separate member on the container 10 or in any suitable manner so as to effect the tipping of the auxiliary container or bucket 16 when the contact member 13 is moved downwardly into the position shown in Figure 1.

The sequence of operation is illustrated in Figures 1, 2 and 3, in the order named, for opening of the circuit. As illustrated in Figure 1, the device is in the fully closed position and is adapted to carry current under operating conditions. The device is initiated in operation by moving the contact member 13 in an upward direction by any suitable means. As illustrated in Figure 2, the contact member 13 moves out of engagement with the fixed contact member 11. As a result, the entire current flow is transferred to the conducting liquid 15. However, since the circuit is not as yet fully open, there will be no arcing between the contact members 11 and 13. It will also be observed that the auxiliary container or bucket 16 is turned slightly toward the horizontal position. When the auxiliary container or bucket 16 is in the full horizontal position it will be observed that it entirely surrounds the lower end of the contact member 13. In this position it will be understood that both of the contact members 11 and 13 are individually surrounded by a container filled with conducting liquid and that the circuit is completed from the fixed contact member through the conducting liquid in the container 10, thence through the conducting liquid in the auxiliary container or bucket 16 to the movable contact member 13.

The continued upward movement of the movable contact member 13 lifts the auxiliary con-

tainer or bucket 16 wholly out of engagement with the remaining liquid in the container 10. Due to the fact that there is no metal-to-metal break, or metal to liquid break, there will be no ionized path created between the contact members. The final break of the circuit will take place entirely between two portions of the conducting liquid 15. From tests which I have made on a circuit breaking device constructed in accordance with my invention, I have found that I can open an electric circuit without the formation of arcs which normally are formed when a like circuit is opened between metallic contact members.

Since certain further changes may be made in the foregoing construction and different embodiments of the invention may be made without departing from the spirit and scope thereof, it is intended that all matters shown in the accompanying drawing or set forth in the foregoing description shall be interpreted as illustrative, and not in a limiting sense.

What I claim is:—

1. An electrical circuit breaking device comprising, in combination, a non-metallic conducting fluid, separable contact means disposed in contact engagement under the surface of said fluid for carrying the main portion of the current of the circuit and disposed on separation thereof to permit the entire flow of current through said fluid, and means for subsequently interrupting the current flow through said fluid between two portions thereof.

2. An electrical circuit breaking device comprising, in combination, a main container, a conducting liquid in said container, a fixed contact member disposed in said container, a movable contact member disposed to engage said fixed contact member underneath the surface of said liquid to carry the main portion of the current of the circuit and on separation to permit the entire flow of current through said liquid, an auxiliary container composed of insulating material and rotatably mounted on said movable contact member and disposed to surround the lower end thereof, and a tipping member mounted on said main container and disposed to tip said auxiliary container as said movable contact member approaches said fixed contact member to permit engagement of said contact members, said auxiliary container being disposed to rotate on withdrawal of said movable contact member from engagement with said contact member to carry therewith a portion of said conducting liquid whereby the circuit is opened between the liquid remaining in said main container and the liquid in said auxiliary container.

3. An electrical circuit breaking device comprising, in combination, an ionizable conducting liquid, separable contact means in contact engagement under the surface of said liquid for carrying the main portion of the current of the circuit and on disengagement thereof permitting the entire flow of current through said liquid, and means for subsequently interrupting the current flow through said liquid between two portions thereof and providing an air gap in the circuit.

4. An electrical circuit breaking device comprising, in combination, a conducting liquid which comprises water and a material dissolved therein providing a source of ions, separable contact means in contact engagement under the surface of said liquid for carrying the main portion of the current of the circuit and on disengagement thereof permitting the entire flow of current through said liquid, and means for subsequently

interrupting the current flow through said liquid between two portions thereof and providing an air gap in the circuit.

5. An electrical circuit breaking device comprising, in combination, a conducting liquid comprising water and a solute which renders the water conducting, separable contact means in contact engagement under the surface of said

liquid for carrying the main portion of the current of the circuit and on disengagement thereof permitting the entire flow of current through said liquid, and means for subsequently interrupting the current flow through said liquid between two portions thereof and providing an air gap in the circuit.

EDMUND O. SCHWEITZER, JR.
